Primary Examiner—Doris V. Coles**Assistant Examiner**—Mimosa De**Attorney, Agent, or Firm**—Thompson Hine & Flory LLP[57] **CLAIM**

The ornamental design of the infant car seat base, as shown and described.

DESCRIPTION

FIG. 1 is a perspective view of the infant car seat base showing the design of our invention with an infant car seat positioned on the base and shown in broken lines. The broken line showing of the infant car seat and handle is for illustrative purposes only and forms no part of the claimed design.

FIG. 2 is a perspective view thereof;

FIG. 3 is a side elevation view thereof; and,

FIG. 4 is a front elevation view thereof.
